UNITED STATES PATENT OFFICE.

JESSE M. GILBERT, OF PARADISE, KANSAS.

GATE-FASTENER.

1,195,202.

Specification of Letters Patent. Patented Aug. 22, 1916.

Application filed December 27, 1915. Serial No. 68,723.

To all whom it may concern:

Be it known that I, JESSE M. GILBERT, a citizen of the United States, residing at Paradise, in the county of Russell and State 5 of Kansas, have invented new and useful Improvements in Gate-Fasteners, of which the following is a specification.

My present invention has to do with means for securing gates and the like in closed position; and it has for its object to provide a device designed more especially for use in conjunction with wire fences and gates, and constructed with a view to securely fastening a gate in closed position, in 10 such manner that there is no liability of the gate being casually released, and yet when desired the gate may by slight manipulation of the device be readily unfastened and released.

20 To the attainment of the foregoing the invention consists in the novel and useful combination hereinafter described and definitely claimed.

In the accompanying drawings which are 25 hereby made a part hereof: Figure 1 is a view showing my novel fastener in closed position and in proper relation to a fence post and an upright at the free end of the gate. Fig. 2 is a view, partly in full lines 30 and partly in dotted lines, showing the manner in which the fastener is opened to permit of ready release of the gate. Fig. 3 is a top plan of the closed fastener. Fig. 4 is a section, taken in the plane indicated by the line 4—4 of Fig. 2, looking downwardly.

35 Referring by numeral to the said drawings 1 is the end post of a fence, and 2, an upright at the free end of the gate.

In putting my invention into effect, I 40 prefer to secure a wire band 3 on the post 1, and to said band I connect the body 4 of the fastener. The said body 4 is preferably formed by bending a strap of metal into loop-shape, Fig. 3, and deflecting the terminals of said arms of the body downwardly, 45 as indicated by 5. At its bight the said body is equipped with an eye 6 for the connection thereof to the band 3.

Pivoted at 7 between the ends of the body 50 4 is one end of a lever 8, having a handle 9 that is preferably loop-shaped, as illustrated, and pivotally-connected at 10 to the said lever is a bail-shaped link 11, that strad-

dles the body 4 and is provided with a hook 12, detachably engaged with a loop or ring 55 13, suitably-secured on the gate upright 2.

With the fastener closed as shown in Fig. 1, it will be manifest that the gate will be tightly secured in closed position; also, that any tendency of the gate to swing open will 60 have the effect of holding the lever 8 more strongly in the closed position. When, however, a person desires to unfasten the gate, it is simply necessary to grasp the handle 9 and move the lever 8 downwardly 65 to a sufficient extent to break the dead center, when the hook 12 will be rendered loose and can be readily disengaged from the loop 13. To fasten the gate, the operation is reversed—i. e., the hook 12 is connected to 70 ring or loop 13, and the lever 8 is swung back to the position shown in Fig. 1 to carry the connection between link 11 and lever 8 above the center of movement of said lever 8, when the gate will be tightly secured in 75 closed position without liability of casual release.

In the position shown in Figs. 1 and 3, the portion 14 of the lever 8 abuts against the body 4 and thereby limits upward movement of the lever.

Two or more apertures 15 may be provided in the lever 8 for the adjustable connection of the link 11, when the same is desired expedient.

The specific construction and relative arrangement of parts as herein described constitute a simple, inexpensive and practical embodiment of my invention. I do, not, however, confine myself to said specific construction and relative arrangement of parts as certain changes in construction may obviously be made without departure from the scope of my claims.

Having described my invention, what I 95 claim and desire to secure by Letters-Patent, is:

1. A device for the purpose described, comprising a body having a deflected portion at one end, a lever pivoted to said deflected portion of the body and having a portion arranged to bring-up against the body, and a link pivoted to the lever back of the deflected portion of the body.

2. A device for the purpose described, comprising a loop-shaped body having de-

flected end arms, a lever pivoted to said arms and having a hand loop and also having a portion adapted to bring-up against the body, and a bail-shaped link arranged to straddle the deflected arms of the body and pivoted to the lever, back of said deflected arms.

Copies of this patent may be obtained for five cents each, by addressing the "Commissioner of Patents, Washington, D. C."

In testimony whereof I have hereunto set my hand in presence of two subscribing witnesses.

JESSE M. GILBERT.
